AUDIO FREQUENCY LIMITING DEVICE

John Hays Hammond, Jr., Gloucester, Mass.

Application March 6, 1933, Serial No. 659,665

9 Claims. (Cl. 179—1)

This invention relates to sound reproducing or recording systems and more particularly to an improved means for preventing overloading of an electro-dynamic sound reproducer or recorder, such as a loud speaker, phonograph record engraving tool, or the like.

In one embodiment of the invention, the field windings of the sound reproducing or recording device are energized by a current which is varied as a function of the input tone current. This may be accomplished by causing an excess in input volume, above a predetermined value, to cut down the field current to such a degree that the response of the device is definitely limited. The invention accordingly prevents the response from reaching the point where distortion or chattering would occur, for example, by reason of the moving element coming into contact with the mechanical stop members.

The invention is also applicable to the cutting of phonograph records and prevents the records from being overcut as a result of loud input volume.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawing forming a part thereof, in which

Fig. 1 illustrates diagrammatically one form of circuit embodying the present invention; and

Fig. 2 is a curve showing the relation between the impressed voltage and the motion of the moving elements.

In the following description and in the claims, parts will be identified by specific names for convenience, but they are intended to be as generic in their application to similar parts as the art will permit.

Referring more particularly to the drawing, a light source 10 is provided, the light from which is focused by means of a lens 11 through an aperture 12 in an aperture plate 13 upon the sound record of a moving photographic film 14. The light which passes through this film is focused by a second lens 15 upon a photoelectric cell 16. This cell is connected through a battery 17 to the primary of a transformer 18.

A phonographic pickup device 22 of well known

form may be provided for use with a disk record. A microphone 24 may also be provided for sound recording purposes and may be connected to the primary of a transformer 25. The secondary of the transformer 18, the winding of the pickup device 22, and the secondary of the transformer 25 may be selectively connected across the input of an amplifier 27 by a three position switch 21 having contacts 19, 23 and 26 which are respectively connected thereto.

The amplifier 27 may comprise, for example, a space discharge amplifying means of standard form, having one or more stages of amplification as desired. The output circuit of the amplifier 27 includes the primary of the transformer 31, the secondary of which may be selectively connected across the armature or moving coil 32 of a loud speaker 33 or across the armature coil 34 of a phonograph record engraving tool 35 by means of contacts 36 and 38 of a double-pole double-throw switch 37.

The output circuit of the amplifier 27 also includes the primary of a transformer 41. The secondary of this transformer is connected in a circuit including a battery 42, rectifier 44 and resistance 45, which may be shunted by a condenser 46 adapted to control the time constant of said circuit. The battery 42 is connected to oppose the flow of current through the rectifier 44 so that no current will be passed thereby until the impressed voltage exceeds the voltage of said battery. The resistance 45 is connected between the filament and grid of a space discharge device 43 so as to control the grid potential thereof.

The plate circuit of the space discharge device 43 includes a secondary 47 of a transformer 52, which serves as a source of plate potential, and the field winding 51 of loud speaker 33 or the field winding 53 of the engraving tool 35, said windings 51 and 53 being connected respectively to contacts 52' and 54 of the switch 37, whereby they may be alternately rendered operative. The primary of transformer 52 is connected to a source of alternating current supply 55. A second secondary 48 of transformer 52 serves to energize the cathode of the device 43. A condenser 56 may be connected across the windings 51 and 53 to control the operating characteristics thereof.

In the operation of the above described system the switch 21 is thrown into an engagement with the contact 19 when it is desired to use the sound film 14. When the phonograph pickup 22 is to be used, the switch 21 is thrown into engagement with the contact 23, and when it is desired to use

the microphone 24 the switch is thrown into engagement with contact 26. In any case the energy is fed to the amplifier 27 where it is amplified and supplied to the transformer 31.

5 If the system is to be used for sound reproduction the switch 37 is thrown into position to engage contacts 36 and 52'. In this case energy from the secondary of the transformer 31 is supplied to the moving coil 32 of the loud speaker 33 and the field winding 51 of this loud speaker is energized by the uni-directional space current of the device 43.

10 Part of the output energy of the amplifier 27 is supplied to the transformer 41 and causes a voltage to be impressed upon the circuit including the rectifier 44. No current will pass the rectifier 44, however, until the impressed voltage exceeds the voltage of the battery 42. When the input current is such that the impressed voltage 15 exceeds this value, unidirectional current will flow through the resistance 45 in the direction of the arrow, thus building up a potential difference across this resistance which is dependent upon the excess of input tone current above the pre-determined value. This causes a negative potential to be placed on the grid of the device 43 which is proportional to this excess of tone current, thereby increasing the impedance of this device 20 and decreasing the space current passed thereby. 25

30 In this way the magnetization current fed to the field winding 51 is decreased, thereby decreasing the motor efficiency of the loud speaker and cutting down the response thereof. Obviously additional grid biasing means may be employed if desired, the amount of biasing potential depending upon the characteristics of the device 43.

35 The various constants are so selected that the normal operation of the loud speaker is not interfered with. But when the input signal is increased to a point such that distortion or rattling would occur, the device 43 functions to reduce the current in the field winding, thus reducing the motion of the moving element so as to keep it within normal limits. The condenser 46 may be 40 of such value that the current variations in resistance 45 are caused to correspond to the average energy level of the signal over a definite time interval corresponding, for example, to a syllable or a musical note, as distinguished from the instantaneous energy level of the sound waves. It 45 is to be understood that the time response of the circuit including rectifier 44 and resistance 45 may be controlled by suitable adjustment of condenser 46.

50 From the above it will be clear that the average energy level is continually changing as the signal changes although it does not change as rapidly as the instantaneous energy level. The average energy level, since it is continually changing, may 55 be called a moving average of the signal energy.

55 Figure 2 shows a curve illustrating a preferred relationship between the impressed voltage and the motion of the moving element. It is seen from this curve that as the impressed voltage increases the motion of the moving element increases uniformly to the point 57. Beyond that point, as the impressed voltage increases, the increase in motion becomes less and less and never reaches a point such that distortion occurs, 60 for example, as a result of the moving element striking the mechanical stops.

65 If the system is to be used for sound recording the switch 37 is thrown into engagement with contacts 38 and 54, thus connecting the armature 70 coil 34 to the secondary of the transformer 31

and the field coil 53 in the plate circuit of the device 43. The operation of the system for sound recording is the same as that just described in connection with the loud speaker, that is, if the tone current increases beyond a predetermined value, the magnetization current in the field winding 53 will be relatively decreased, thus preventing the engraving tool 35 from overcutting the record.

75 Only so much of the circuits have been shown 10 as is necessary to an understanding of the invention. The various details are understood to be of standard form and will be readily apparent to a person skilled in the art. The invention is not to be limited to any specific construction, 15 but may be embodied in various forms without departing from the spirit thereof. It is only to be limited in accordance with the following claims when interpreted in view of the prior art.

20 What is claimed is:

1. The method of operating an electro-dynamic sound reproducing or recording device having a variable magnetic field and exciting means therefor which comprises utilizing an increase in average input sound energy above a predetermined 25 minimum to decrease the field excitation whereby the response of said device is prevented from exceeding a predetermined value.

2. The method of operating an electro-dynamic sound reproducing or recording device having armature and field windings which comprises causing the field excitation to vary inversely as the average armature excitation when the average armature excitation exceeds a predetermined value whereby the response of said device is prevented from exceeding a predetermined value.

3. In a sound reproducing or recording system having an electro-dynamic reproducing or recording device provided with a field winding, means to energize said winding, and means dependent upon the average input sound energy to decrease said energization when said average input energy exceeds a predetermined value.

4. In a sound reproducing or recording system having an electro-dynamic reproducing or recording device provided with a field winding, means to energize said winding, a space discharge device adapted to control said energization, and means to increase the impedance of said space discharge device when the input sound energy exceeds a predetermined value whereby to decrease said field energization.

5. A sound reproducing or recording system comprising a source of sound energy, amplifying means therefor, an electro-dynamic device having 55 armature and field windings, means energizing said armature windings in accordance with said amplified energy, means to energize said field windings, and means to decrease said last mentioned energization when the average level of said sound energy exceeds a predetermined value 60 whereby to limit the response of said device.

6. A sound reproducing or recording system comprising a source of sound energy, amplifying means therefor, an electro-dynamic device having 65 armature and field windings, means energizing said armature windings in accordance with said amplified energy, means to energize said field windings, and means to decrease said last mentioned energization when the average level of 70 said sound energy exceeds a predetermined value comprising a variable impedance device, a resistance adapted to control the impedance thereof, said resistance being connected in a circuit including a rectifier and a source of potential adapt- 75

ed to oppose the flow of current in said circuit, and means to impress on said rectifier a potential dependent upon the input sound energy, an increase in potential drop across said resistance being 5 adapted to increase the impedance of said device.

7. In a sound recording system, a recording device having an armature controlled by the sound energy and a field energized from an independent 10 source, and means controlled by the average level of the sound energy for reducing the field energization when said average level exceeds a predetermined value to prevent overcutting of adjacent sound tracks.

8. In a phonograph system, a pick-up device

for sound energy, a translating device fed thereby, a field in said translating device, exciting means therefor, and means controlled by the average energy from said pick-up device for reducing the field excitation when said average energy exceeds a predetermined value. 5

9. In a sound record system, a pick-up device for sound energy, a translating device fed thereby, a field in said translating device, exciting means therefor, and means controlled by a moving average of the energy from said pick-up device for reducing the field excitation when said average energy exceeds a predetermined value. 10
